DESIGN FOR A BILLBOARD FRAME MOLDING

Roger W. Olmsted, San Mateo, Calif.

Application March 18, 1946, Serial No. 127,636

Term of patent 14 years

(CL. D13—6)

To all whom it may concern:

Be it known that I, Roger W. Olmsted, a citizen of the United States and a resident of San Mateo, county of San Mateo, State of California, have invented a new, original, and ornamental Design for a Billboard Frame Molding, of which the following is a specification, reference being had to the accompanying drawing, forming a part thereof.

Fig. 1 is a front elevational view of a billboard frame molding showing my new design; and

Fig. 2 is a side elevational view thereof.

I claim:

The ornamental design for a billboard frame molding, substantially as shown.

ROGER W. OLMSTED.
